UNITED STATES PATENT OFFICE.

CARL J. SCHWARZE, OF ADRIAN, MICHIGAN.

ELECTRICALLY-OPERATED SOUND-PRODUCER.

1,050,239.

Specification of Letters Patent. Patented Jan. 14, 1913.

Application filed July 28, 1911. Serial No. 640,974.

To all whom it may concern:

Be it known that I, CARL J. SCHWARZE, a citizen of the United States of America, residing at Adrian, in the county of 5 Lenawee and State of Michigan, have invented certain new and useful Improvements in Electrically-Operated Sound-Producers, of which the following is a specification, reference being had therein to the 10 accompanying drawings.

The invention relates to electrically operated sound producers, being more particularly designed for use as an alarm device on vehicles such as automobiles.

15 It is the object of the invention to obtain an efficient and compact arrangement of the operating parts and one which may be readily manufactured and assembled at low cost of construction.

20 To this end the invention consists in the peculiar construction, arrangement and combination of parts as hereinafter set forth.

In the drawings,—Figure 1 is a central 25 longitudinal section through the apparatus and substantially on line $x-x$ Fig. 2; Fig. 2 is a plan of the electromagnets; and Figs. 3 and 4 are perspective views of one of the magnet coils and the filler block for forming in connection therewith, the spool for the condenser windings.

My improved apparatus is completely housed in a suitable casing preferably comprising the portions A, B and C. The portion A is of cylindrical form and of magnetic metal, being arranged around the electromagnet coils and coöperating therewith. The portion B is a cap slightly coned and provided at its center with a nipple D 35 for attachment to the horn or megaphone. The portion C is a cap for the opposite end of the case and incloses such parts as are outside of the cylindrical portion A.

Within the case is arranged the sound 40 producer which comprises essentially a diaphragm E arranged across the case adjacent to the cap B and clamped thereby between washers or rings F and G against the case portion A. Adjacent to this diaphragm is a plate H of magnetic metal 45 which is also clamped by the cap B to the case portion A. The plate H is centrally apertured and is provided with a correspondingly apertured bearing I preferably 50 formed of non magnetic metal and in which is slidingly located a striker rod J.

Arranged concentrically around this striker rod are a plurality of magnet coils K having pole pieces L which exert a balanced pull upon a disk armature M mounted upon the striker J. The striker J is also connected to the vibrator spring N of the make and break circuit closing device in which O is the coöperating adjustable contact secured to the arm P having an insulated support on the frame.

Q is a spring arm or buffer arranged in the path of the striker J at the opposite end from the diaphragm P.

With the construction as thus far described the passage of the electric current through the circuit interrupter and the coils of the magnet will cause a vibratory movement of the armature which is transmitted to the striker J and will cause the latter to impinge upon the diaphragm E. The resiliency of this diaphragm will return the striker and the buffer Q will operate in conjunction with the magnetic pull to increase the force of the blow.

To facilitate the construction of the magnet the several coils which surround the core or pole pieces L are individually wound and are then attached to the plate H. Each coil is wound between the insulator flanges R which are fashioned to form complementary parts of a circular disk concentric with the axis of the casing. Thus when all of the segments are assembled they together form peripheral flanges 55 leaving a groove in which a condenser may be located. This condenser is preferably formed of a pair of wires wound together around the magnets in the groove between the peripheral flanges and to form a circular body on which these windings may be placed, filler blocks S are arranged in the spaces between the coils K. The arrangement is one which utilizes practically 60 all of the space within the casing A and at the same time it is a construction which may be easily manufactured and the parts of which can be quickly assembled.

What I claim as my invention is:

1. The combination with a plate of magnetic material, of a series of magnetic cores secured to said plate and arranged in a circle thereupon, spools on said cores forming complementary portions of a circular spool, magnet coils wound on the individual cores, and a coil surrounding all of the cores and individual coils.

2. The combination with a plate of magnetic material, of a plurality of magnetic cores detachably secured to said plate and projecting laterally therefrom, flanges on 5 said cores forming complementary portions of circular flanges concentric with said plate, individual magnetic coils wound upon said cores between said flanges, and a coil wound between said flanges and surrounding all of 10 the cores and coils thereon.
3. The combination with a base plate, of a plurality of magnet cores detachably secured thereto and arranged concentrically thereupon, flanges upon said individual 15 cores forming complementary portions of circular flanges surrounding all of the cores, an individual coil wound upon each core, filler blocks between said coils forming in connection therewith a circular body, and 20 a coil wound upon said coils and filler blocks between said flanges.
4. The combination with a cylindrical case, of a cap therefor, a plate extending across said case and clamped between the 25 same and said cap, a plurality of magnet cores detachably connected to said plate, spool flanges on said cores forming complementary portions of a large spool concentric with the axis of said case, individual coils 30 wound on said cores between the flanges thereof, fillers complementary to said coils to form a cylindrical body, and a coil wound around all of said individual coils and fillers and between said flanges.
- 35 5. The combination with a cylindrical case, of a plate extending across one end of said case detachably secured thereto, a plurality of magnet cores detachably secured to said plate and projecting therefrom 40 being arranged concentrically within said

case, spool flanges on said cores forming complementary portions of a large spool filling said cylindrical case, magnet coils wound upon the individual cores and arranged adjacent to each other, fillers for the spaces 45 between said coils complementary thereto to form a cylindrical body, and a coil surrounding all of said coils and fillers and wound between the flanges of said spool.

6. The combination with a cylindrical 50 case, of a detachable cap therefor, an adjacent plate and vibratory diaphragm extending across said case and clamped between the same and said cap, a plurality of magnet pole pieces secured to said plate and arranged concentrically within said case, spool flanges on said cores forming complementary portions of a large spool filling said case, coils wound upon the individual cores, 55 fillers in the spaces between said coils forming complementary portions of a cylindrical body, a coil surrounding all of said individual coils and fillers and arranged between said flanges and within said cylindrical case, a striker extending axially within said case 60 adapted to impinge against said diaphragm, a circular armature secured to said striker and extending over the poles of the several cores, a make and break circuit closer coöoperating with said armature, and 65 a cap for closing the opposite end of said case and housing said make and break circuit closer.

In testimony whereof I affix my signature in presence of two witnesses.

CARL J. SCHWARZE.
